UNITED STATES PATENT OFFICE.

ERNEST W. KUMMER, OF EDGEWATER, COLORADO, ASSIGNOR OF ONE-HALF TO GEORGE C. KEECH, OF DENVER, COLORADO.

GASOLINE-VAPORIZING GLAND.

Application filed September 14, 1923. Serial No. 662,673.

To all whom it may concern:

Be it known that I, ERNEST W. KUMMER, a citizen of the United States, residing at Edgewater, in the county of Jefferson and State of Colorado, have invented certain new and useful Improvements in Gasoline-Vaporizing Glands, of which the following is a specification.

This invention relates to means for heating the incoming gases of an internal combustion engine and has for its principal object the provision of a device of this character which will be economical to manufacture, can be quickly and easily installed without changing the present construction and which will employ the exhaust gases as a heating medium.

Other objects and advantages reside in the detailed construction of the invention, which result in simplicity, economy and efficiency, and which will become more apparent from the following description.

In the following detailed description of the invention, reference is had to the accompanying drawing which forms a part hereof. Like numerals refer to like parts in all views of the drawing and throughout the description.

In the drawing:

Fig. 1 is a horizontal cross section looking down through the cylinder block of an internal combustion engine, on the line of the inlet and exhaust valve ports, showing the invention in operative position.

Fig. 2 is a side elevation of the complete invention.

Fig. 3 is a longitudinal cross section through the invention, taken on the line 3-3, Fig. 2.

In Fig. 1 the cylinder block of an engine is shown at 10, in which, the various parts are designated as follows: intake ports 11, exhaust ports 12, cylinders 13 (designated in order (1), (2), (3), and (4)), intake manifold 14, exhaust manifold 15, manifold clamps 16, manifold clamp bolts 17, and valve push rods 18.

The invention comprises three uniformly spaced rings 19, 20, and 21, 19 and 21 being end rings and 20 being the middle ring. Rings 19, 20, and 21 are each provided with a peripheral raised shoulder 22 at their middles. The spacing of the rings corresponds

to the spacing of the intake and exhaust ports 11 and 12 of the engine.

Rings 19, 20 and 21 are held in spaced relation by two tubes 23, which pass completely through the ring 20 and terminate in the interior of each of the rings 19 and 21, as shown at 24 and 25 respectively, in opposite facing bends. The tubes 23 pass through the raised shoulders 22 of the rings which are pressed to tight joint thereon. In the ring 20 the tubes 23 are bent apart, as shown at 26, in order to increase the amount of tube surface within the ring.

In applying the invention to an engine, the intake and exhaust manifolds 14 and 15 are removed, the manifold gaskets and glands are removed and replaced by the invention, as shown in Fig. 1. The projecting edges of the rings 19, 20 and 21 fit into the port holes 11 and 12 of the cylinder block 10, and into the openings of the intake and exhaust manifolds 14 and 15, replacing the removed glands. The shoulders 22 act to replace the removed gaskets between the manifolds and the cylinder block 10.

Two of the devices are required for a four cylinder engine and are so placed that the tube terminals 25 turn inward the exhaust ports 12 of the first and fourth cylinders. The terminals 24 will then turn outward from the exhaust ports 12 of the second and third cylinders and the rings 20 will register with the two intake ports 11 of the engine. The manifolds are replaced and clamped against the invention by the usual clamps 16 and clamp bolts 17.

The spacing between the tubes 23 is such that they will pass above and below the clamp bolts 17, which occupy the broken line positions indicated at 17 in Fig 2.

The action of the device is as follows: The cylinders fire in the order of 1, 2, 4, 3. A portion of the hot gases from the exhaust of cylinder 1 is caught by the extremities 25 of the tubes 23 and is forced into the tubes by the pressure of the exhaust. The exhaust of cylinder No. 2 follows closely upon that of cylinder No. 1 and creates a suction at the outward turned extremities 24 of the tubes 23, which assists in rapidly drawing the hot gases from No. 1 exhaust through the tubes.

This action is repeated in the other device on cylinders 3 and 4, where the ex-

haust of cylinder 3 follows closely upon that of cylinder 4 and assists in drawing the hot gases from cylinder 4 through the tubes.

5 This intermittent, yet rapid, succession of hot gases through the tubes 23, causes them to become highly heated and present a heated surface to the incoming gases from the intake manifold to assist in atomizing 10 and gasifying the gasoline and air mixture therein, thereby increasing the combustibility of the gases and causing a cleaner and more rapid burning.

15 It will be noted that the gases are pre-heated at the very point they enter the combustion chamber, not at the carburetor or in the manifold as in other devices of this type. This prevents any subsequent condensation of the suspended liquid on its passage to the combustion chamber.

20 While a specific form of the improvement has been described and illustrated herein, it is desired understood that the same may be varied, within the scope of the appended 25 claims without departing from the spirit of the invention.

Having thus described the invention, what is claimed and desired secured by Letters Patent is:—

30 1. A hydro-carbon vaporizing device for internal combustion engines comprising the combination of a series of glands adapted to be placed between the manifolds and the cylinders of said engines, and tubes inter- 35 connecting and holding said glands in spaced relation, said tubes communicating between the exterior glands of said series and passing completely through the interior glands thereof.

40 2. A hydro-carbon vaporizing device for

internal combustion engines comprising a series of glands adapted to be placed between the manifolds and the cylinders of said engines, and tubes interconnecting said glands, said tubes terminating in the exterior glands of said series and passing completely through the interior glands thereof, the terminating extremities of said tubes being turned toward said cylinders in one of the exterior glands and away from said cylinders in the other of said exterior glands. 45 50

3. The combination with an internal combustion engine, of a series of glands connecting the manifolds with the cylinder ports of said engine and tubes interconnecting said glands, said tubes terminating in and communicating between the glands at the exhaust ports and passing through the glands at the intake ports. 55

4. The combination with an internal combustion engine having four cylinders, of a series of glands connecting the manifolds with the ports of said cylinders and tubes interconnecting said glands, said tubes terminating in the glands at the exhaust ports 60 of the first and fourth cylinders of said engine in inward turned extremities, in the glands at the exhaust ports of the second and third cylinders of said engine in outward turned extremities and passing completely through the glands at the intake ports so that the gases will be forced into said tubes by the exhaust of the first and fourth cylinders and will be drawn through said tubes and thus across the intake ports 65 by the exhaust of the second and third cylinders. 70 75

In testimony whereof, I affix my signature.

ERNEST W. KUMMER.
